UNITED STATES PATENT OFFICE

2,122,868

CLAMP

Erving B. Morgan, Grand Rapids, Mich., assignor
to American Seating Company, Grand Rapids,
Mich., a corporation of New Jersey

Application June 1, 1937, Serial No. 145,686

2 Claims. (Cl. 287—58)

The present invention relates to clamps and more particularly to clamps for maintaining a pair of telescopically slideable members in longitudinally adjusted position. The clamp of the instant invention is in the nature of an improvement or modification of the clamp shown in United States Letters Patent No. 2,039,973, issued May 5, 1936, on application filed by me December 22, 1933, Serial No. 703,634.

The primary objects of the instant invention are to provide a clamp assembly of the general character above indicated which is particularly well adapted for use in maintaining a seat disposed forwardly of a school desk at a predetermined or adjusted height from the floor and/or in properly adjusted vertical relation to the desk; and, to provide such a clamp assembly which is convenient and efficient in service, which is readily adjustable in use, and which is economical in manufacture.

An illustrative embodiment of the invention is shown in the accompanying drawing, wherein:

Figure 1 is a front elevational view of a base support for a vertically disposed tubular pedestal within which a chair or table top supporting column is longitudinally slideable and vertically adjustably maintained;

Figure 2 is an enlarged sectional view thereof on line 2—2 of Figure 1;

Figure 3 is a sectional view on line 3—3 of Figure 2;

Figure 4 is a view of the base supported tubular pedestal, its telescopically slideable chair or table top supporting column and the clamp for maintaining the pedestal and column in longitudinally vertically adjusted position; and

Figure 5 is a perspective view of the clamp without its tightening bolt.

Referring then to the drawing wherein like parts of the structure shown are designated by the same numerals in the several views, a base support 10 of cast or stamped sheet metal and having oppositely disposed depending feet 11, is provided with a vertically disposed tubular pedestal 12 secured thereto in any convenient conventional manner.

A supporting column 13 for supporting a chair or table top and here shown as of tubular metal stock is telescopically slideable within the tubular pedestal 12. The tubular pedestal is provided with a pair of spaced parallel slots 15, 16 transversely of its length, the slot 15 being in the form of a recess adjacent the upper end of the tubular pedestal 12.

A bifurcated clamp, generally designated 16, embraces the tubular pedestal 12, its opposite legs 17, 18 each being respectively provided with a pair of spaced laterally disposed inwardly turned ears 19, 20. The ears 19 which project laterally and inwardly toward each other are seated within the upper slot or recess 15 and bear against the outer wall of the chair or table top supporting column 13 whereas the ears 20 are seated within the lower slot 16 and engage the outer wall of the supporting column 13.

Means for compressing the legs 17, 18 of the clamp 16 toward each other for maintaining pedestal 12 and its telescoping column 13 in longitudinally vertically adjusted position comprises the threaded bolt 21 projected through the bolt receiving aperture 22 in the leg 17 of the clamp and its internally screw threaded sleeve nut 23 projected through the receiving aperture 24 of the leg 18 of the clamp.

Tightening the sleeve nut 23 on its threaded bolt 21 causes the legs 17, 18 of the clamp 16 to be drawn toward each other which in turn causes the pair of ears 19, 20 to more tightly engage the outer wall of the column 13 whose opposite outer surface is thus caused to tensionally and frictionally engage the inner surface of the tubular pedestal 13.

It will thus be seen that the clamp assembly herein shown and described is particularly well adapted for use in maintaining a seat disposed forwardly of a school desk at a predetermined or adjusted height from the floor and/or in properly adjusted vertical relation to the desk. This clamp assembly is convenient and efficient in service, is readily adjustable in use and is economical in manufacture and while but one specific embodiment of the invention has been herein shown and described, it will be understood that certain details of the construction shown may be altered or omitted without departing from the spirit of the invention as the same is defined by the following claims.

I claim:

1. In a device of the class described, a tubular member provided with a pair of spaced parallel slots disposed transversely of its length, a member telescopically disposed within said tubular member, a bifurcated clamp embracing the tubular member and having one leg provided with spaced laterally disposed ears each seated within a slot and each adapted to engage the wall of said second member, and means for compressing the legs of the clamp toward each other for maintaining the wall of said member in frictional engage- 55

ment with the inner wall of said tubular member to maintain said members in longitudinally adjusted position.

2. In a device of the class described, a tubular member provided with a recess disposed transversely of its length adjacent one end thereof and with a slot disposed through its wall in spaced parallel relation to said recess, a member telescopingly disposed within said tubular member,
- 5 10 a bifurcated clamp embracing the tubular mem-

ber and having one leg provided with spaced laterally disposed ears respectively seated within said recess and within said slot adapted to engage the wall of said second member, and means for compressing the legs of the clamp toward each other for maintaining the wall of said member in frictional engagement with the inner wall of said tubular member to maintain said members in longitudinally adjusted position.

5 ERVING B. MORGAN. 10
